UNITED STATES PATENT OFFICE.

FRANK SHUMAN, OF PHILADELPHIA, PENNSYLVANIA, ASSIGNOR TO THE SIMPLEX CONCRETE PILING COMPANY, OF WASHINGTON, DISTRICT OF COLUMBIA, A CORPORATION OF THE DISTRICT OF COLUMBIA.

APPARATUS FOR FORMING PILES.

1,281,860.

Specification of Letters Patent. Patented Oct. 15, 1918.

Application filed October 2, 1915. Serial No. 53,730.

To all whom it may concern:

Be it known that I, FRANK SHUMAN, a citizen of the United States, residing in Philadelphia, Pennsylvania, have invented an Apparatus for Forming Piles, of which the following is a specification.

My invention relates to certain improvements in driving forms and in the process of driving the forms into the ground with a casing.

The main object of the invention is to provide means for driving the pile form with the casing so that when the casing is driven to the depth desired the pile form can be removed without withdrawing the casing.

The invention also relates to the particular construction of the pile form whereby the withdrawal of the form is accomplished.

The invention is mainly applicable to a tapered, round or square pile, but in soft ground it can be adapted to straight cylindrical piles.

In the accompanying drawings:

Figure 1 is a longitudinal section, showing a pile form with the casing driven into the ground to the depth desired;

Fig. 2 is a longitudinal sectional view, showing the pile form partly removed;

Fig. 3 is a sectional view, showing the casing in the ground and the pile form entirely removed and concrete within the casing;

Fig. 4 is a view illustrating a modification in which the casing is longitudinally corrugated instead of being transversely corrugated, as illustrated in Fig. 1;

Fig. 5 is a sectional plan view on the line *a—a*, Fig. 4;

Fig. 6 is a view illustrating a modification of the means for coupling the two sections of the pile form;

Fig. 7 is a sectional view showing the joint between the two sections of the casing; and

Fig. 8 is a view of a modification showing different forms of indentations from the corrugations.

In the drawings, I have illustrated a pile form made in three sections, but it will be

understood that it can be made in as many sections as desired, according to the depth which it is desired to drive the pile.

1 is the pile form. 2 is the corrugated casing. 3 is the driving head of the usual construction. The pile form, as stated above, is made in three sections 4, 5 and 6. The lower section 4 has a tapered end 7 forming the point of the pile form. The pile form is gradually tapered, as shown, and there is a central tubular spindle 8 extending substantially the full length of the pile and this spindle is directly connected to the driving head 3 and while I have shown the spindle tubular, it may be solid in some instances.

A pin 9 extends through flanges on this driving head and through the upper end of the tubular spindle 8. In the present instance, each section has two independent flanges, which extend to form bearings for the spindle 8. The upper flange of each section forms an abutment for a transverse pin carried by the spindle 8. The flange 6^a of the upper section 6 forms the abutment for the pin 10. The flange 5^a forms the abutment for the pin 11 and the flange 4^a forms the abutment for the pin 12. The pin 11 is spaced a greater distance from the flange 5^a than the pin 10 from the flange 6^a and the pin 12 is a greater distance from the flange 4^a than the pin 11 from the flange 5^a so that when it is desired to withdraw the several sections, as the spindle 8 is withdrawn by any suitable mechanism, the pin 10 first comes in contact with the flange 6^a and lifts the section 6 a given distance before the pin 11 comes in contact with the flange 5^a, and when the pin 11 comes in contact with said flange it lifts the section 5 in advance of the section 4, as the pin 12 will not come in contact with the flange 4^a until the section 5 is raised a given distance, so that by this means only a section at a time is withdrawn from the tight fitting casing. The moment the sections move, then they are released from the casing and it is a comparatively easy matter to remove the entire pile form from the casing.

As will be noticed from Figs. 1, 2, and 3

100

of the drawings the casing is also made in sections of any number desired, depending greatly upon the width of the plate from which the sections are made and each of 5 these sections of the casing is corrugated transversely of any size desired, depending considerably upon the character of the ground into which the pile form is to be driven. One section preferably extends into 10 an adjoining section in the manner shown in Fig. 7, and the lower section has a cap at the bottom which incloses the end of the pile form. The corrugated casing is driven into the ground with the pile form and the earth 15 enters the corrugations and aids materially in holding the casing in the position to which it is driven. The walls of the pile form are smooth and bear only upon the high points of the corrugations so that the 20 frictional resistance of the ground is very much greater than that of the driving form and when the driving form is removed the corrugated casing will remain in the ground, particularly when the pile form is made in 25 sections and one section at a time is removed from the casing. After the pile form is removed, then the casing is filled with concrete in the usual manner. The concrete will conform to the corrugations of the casing and 30 this adds materially in holding the finished pile in the proper position in the ground.

In some instances, the corrugations may be vertical instead of transverse, as illustrated in Figs. 4 and 5, in which 2^a is the 35 corrugated casing encircling the pile form in the manner shown in Fig. 1.

Instead of pins 10, 11 and 12, a double headed bolt may connect the two sections, as illustrated in Fig. 6, the heads of the 40 bolts being spaced apart to allow a certain amount of play between the sections.

I preferably make the lower portion of each shell section plain, as at 13, Fig. 7, and form a shoulder 14 so that this plain 45 portion can enter the end of an adjoining section, and said section will have its true bearing against the shoulder.

I also preferably make the sections of the pile driving form and the sections of 50 the casing so that the joints of the driving form will not align with those of the casing in order that one section of the shell will always be held by the next lower section of the pile driving form. The sections of the 55 pile driving form may be quite short so that at all times there will be a sufficient number of lineal feet of the section of the pile driving form resting in the section of the shell and there will be no danger of the shell lifting 60 out of the ground, although, in some instances, owing to the great friction of the corrugated shell in the ground, it may be advisable to use long sections for the pile form.

65 In very short piles, it is not absolutely

necessary to make the pile driving form in sections, nor is it necessary to make the shell in sections.

When the form, with the shell, is driven, the friction of the earth will hold the shell 70 so that when the pile form is removed it will readily pull away from the shell, leaving it in the ground.

The details of the construction of the pile driving form and the shells can be 75 greatly varied without departing from the principles of holding down one section of the shell with one or more sections of the pile driving form, while the topmost section is lifted. For instance, a perfectly smooth 80 shell may be made without the corrugations, when made of sufficiently heavy sheet metal to withstand the pressure of the ground, and it can be used if the sections of the pile driving form are made very short so that at 85 all points there are one or more sections of the pile driving form holding down a section of the shell when the upper sections of the pile driving form are being lifted. When the last form is being removed it will 90 not have a tendency to draw the shell, owing to the fact that the entire shell is held by the surrounding earth. The corrugations of the shell may be straight or may be formed spirally, as desired, and the depth 95 of the corrugations may be modified without departing from the essential features of the invention.

While I have shown in the main figures the shell as corrugated, it will be understood 100 that it may be indented in any manner desired, as illustrated in Fig. 8, so as to increase the frictional surface against which the earth impinges, the indentations being such that their high points only bear against 105 the smooth portion of the pile form.

I claim:

1. The combination of a pile form made in sections substantially the full diameter of the pile to be formed, one section being 110 superimposed upon another; and means for loosely coupling the sections so that, when the form is withdrawn, the upper section is released and partly withdrawn before the following section is released.

2. The combination in a pile form, of a series of short sections substantially the full diameter of the pile to be formed, one section being superimposed upon another; a spindle extending longitudinally through 120 the several sections; and a driving head connected to the spindle and arranged to rest on the upper section of the pile form, said spindle being loosely connected to the sections of the pile form so that after the pile 125 is driven the sections can be progressively removed.

3. The combination in a pile form, of a series of short sections, one superimposed upon another, each section having an in- 130

ternal flange near each end; a spindle extending through the several sections; and pins carried by the spindle and arranged to engage the flanges of the sections.

5 4. The combination in a tapered pile form, of a series of sections, one superimposed upon another, internal flanges on each

section; a central tubular spindle extending throughout the entire length of the pile form and carrying a series of transverse ¹⁰ pins arranged to engage the flanges of the sections; and a driving head secured to the tubular spindle.

FRANK SHUMAN.
